DEVICE FOR PROVIDING REFRIGERANTS
IN CONTAINERS

Leo M. Harvey, La Canada, and Herbert Harvey
and Reuben Hill, Los Angeles, Calif.; said
Herbert Harvey and said Hill assignors to said
Leo M. Harvey

Application June 23, 1939, Serial No. 280,813

15 Claims. (Cl. 226—19)

This invention relates to the refrigeration of perishable products and relates more particularly to means for refrigerating cartons or containers holding products requiring refrigeration. A general object of this invention is to provide a simple, practical and efficient device for forming or providing a refrigerant in containers or cartons holding perishable or refrigerable products.

In the distribution and marketing of perishable products, such as ice cream, etc., it is the general practice, where the product is to be retained in a container for some time, to arrange the container in an outer carton and to place blocks of dry ice (solidified CO₂) in the outer carton to maintain the product at a suitable low temperature. The period which the product is to remain in the package is determined or estimated and the quantity of dry ice required to preserve the given quantity of the product for said given period is then ascertained or estimated. The dry ice is then weighed and placed in the outer carton as advantageously as possible. This practice has many disadvantages. The handling and the weighing of the dry ice blocks are time consuming operations and the estimated quantity of the refrigerant required is many times incorrect. The dry ice blocks cannot be arranged to maintain an even temperature throughout the inner container and its contents, with the result that a portion of the product may spoil or become unfit for use while the other parts of the product may be maintained at an excessively low temperature. Furthermore, with the usual practice, it is necessary to keep on hand a substantial supply of the dry ice blocks with the accompanying loss through heat absorption.

Another object of this invention is to provide a device for producing dry ice or CO₂ snow in an outer container to preserve or refrigerate the product contained in an inner container disposed in said outer container.

Another object of this invention is to provide a device for refrigerating a container holding a standard food container in spaced relation to its inner walls and that is adapted to discharge CO₂ into the space or spaces in the outer container in such a manner that a body or jacket of solidified CO₂ forms about the inner container to assure the substantially uniform cooling or refrigeration of the inner container and its contents.

Another object of this invention is to provide a device of the class mentioned that may be readily manipulated or controlled to produce a refrigerant body in the outer container capable of maintaining a given quantity of the perishable

product at a given temperature for a given period, thus eliminating all guess work in the packaging and refrigerating operation.

Another object of this invention is to provide a device of the character mentioned embodying an indicating means or timing means made operative upon initiating the discharge of the CO₂ into the package and clearly indicating to the operator the quantity of the CO₂ delivered into the package so that the operator may terminate the delivery of the CO₂ at the correct time for the preservation of a given quantity of the product for a given period.

Another object of this invention is to provide a device of the character mentioned in which the indicating means or timing means need not control the CO₂ discharge valve but may merely serve as a timer by means of which the operator times the period of the CO₂ discharge. This relation between the timing means and the manually controlled discharge means is important as it allows the operator to inject a larger or smaller quantity of CO₂ refrigerant into the package or carton, as conditions may require, while aware or informed of the duration of the discharge and, therefore, of the amount of the refrigerant dispensed.

Another object of this invention is to provide a device of the character mentioned adapted to receive the open end of a carton and to automatically spread the flaps of said open end of the carton in such a manner that the carton end is fully open for the reception of the refrigerant or CO₂.

Another object of this invention is to provide a device of the character mentioned embodying effective means for sealing with the carton at its open end to reduce or prevent the loss of the refrigerant from about the carton.

Another object of this invention is to provide a device of the character mentioned embodying novel means adapting the device for the refrigeration of containers of different sizes and capacities.

Another object of this invention is to provide a device of the character mentioned embodying simple, yet very effective valve means and valve control means governing the discharge of the refrigerant or CO₂ into the carton or package.

The various objects and features of my invention will be fully understood from the following detailed description of a typical preferred form and application of the invention, throughout which description reference is made to the accompanying drawings, in which:

Fig. 1 is a horizontal detailed sectional view of the device of the present invention, illustrating in broken lines the position assumed by the carton when entered in the carton receiving chamber. Fig. 2 is a front elevation of the plunger or follower for temporarily retaining the carton in the refrigerant receiving position. Figs. 3 and 4 are vertical detailed sectional views taken substantially as indicated by lines 3—3 and 4—4, respectively, on Fig. 1, and Fig. 5 is a fragmentary horizontal sectional view taken as indicated by line 5—5 on Fig. 4.

The device of the present invention may be said to comprise, generally, a body or case 10 having a carton receiving compartment A, a valve compartment B, and a coil compartment C, means 11 in the compartment A conditioning a carton X for the reception of the refrigerant, means 12 in the compartments B and C for conducting or delivering the refrigerant to the carton X, an operating means 13 for operating and controlling the means 12, and a timing means 14 operated by the means 13 and adapted to time the discharge of the refrigerant into the container X.

The body or case 10 is a hollow partitioned structure containing and carrying the various elements of the device and adapted to receive the cartons X to be refrigerated. The case 10 may be constructed of any suitable material and is thermally insulated at the points or portions requiring such insulation. This insulation has been omitted from the drawings to simplify the disclosure. The compartment A for receiving the cartons X is defined by what may be considered as forwardly projecting walls 15 and a rearwardly flaring apron 16. The walls 15 are angularly related and joined to form a tube and to define a polygonal opening 17 which constitutes the forward or outer portion of the chamber A. The opening 17 is shaped and proportioned to rather accurately receive the cartons X. The forward end of the opening 17 is normally open to freely receive the cartons. The rear end portions of the walls 15 are suitably fixed or secured in the apron 16. The apron 16 extends rearwardly and laterally at an angle to the walls 15 and a vertical partition 7 extends across the rear end of the apron 16. The apron 16 and the partition 7 define a flaring space or opening joined with the opening 17 and constituting the inner portion of the chamber A. The apron 16 is suitably secured or fixed to the partition 7. As illustrated in Fig. 4 of the drawings the opening 17 and the remainder of the compartment A are designed to receive square or rectangular cartons X, it being understood that the opening 17 and the remainder of the compartment A may be of other configurations to receive cartons of other shapes. The carton X illustrated in the drawings may be considered as a carton of the general character fully described and claimed in the co-pending application of Leo M. Harvey and Reuben Hill, entitled "Container," filed June 23, 1939, Serial No. 280,819.

The compartments B and C are located behind or at the rear of the carton receiving compartment A. The compartments B and C may be defined by spaced side walls 18, a rear wall 19, the partition 7 and a horizontal partition 20. The compartment B is preferably positioned above the compartment C and is closed at its upper side by a top 21. The compartment C is closed at its lower end by a bottom wall 22. It will be understood that the several walls and partitions de-

fining the several compartments of the case 10 may be secured together in any suitable or selected manner. The case 10 may be mounted on a suitable vertical support or horizontal support, as desired. In the case illustrated spaced lugs 23 project laterally at the rear portion of the case 10 to facilitate its attachment to a support.

The means 11 for conditioning the carton X to receive the CO₂ is provided in the inner portion of the compartment A and is operable to spread the free inner end flaps F of the carton X and to engage or seal with the carton so that the CO₂ may freely discharge into it with little or no loss. The means 11 includes an abutment 24 secured 10 to the forward side of the partition 7 to project forwardly in the compartment A. The abutment 24 presents forwardly facing surfaces 25 for engagement by the carton flaps F. The surfaces 25 incline or curve rearwardly and laterally to 15 effect a further or substantially complete opening of the flaps as the carton is moved inwardly. The surfaces 25 are adapted to spread the flaps F to the positions indicated in Fig. 1 where the inner end of the carton X is fully open. The 20 means 11 may further include rearwardly flaring surfaces 26 on the interiors of the walls 15 designed to facilitate or allow the above described spreading of the flaps F by the surfaces 25. When the carton X is moved inwardly through 25 the opening 17 the resiliency of the flaps F and the carton walls urges the flaps F outwardly against the inner sides of the walls 15 and when the carton approaches the inner end of the opening 17 the flaps slide along the surfaces 26 30 and spread under the influence of the said resiliency. The partially open flaps F come into engagement with the surfaces 25 and are fully opened by this engagement by the time the carton X reaches its final position for the reception 35 of the CO₂.

The means 11 further includes a sealing element 27 for sealing with the inner end portion of the carton X when the carton is in position to receive the refrigerant. The abutment 24 has a central opening 28 and a plate 29 is secured or 40 fixed in the opening 28. A recess or groove 30 is provided in the outer edge of the plate 29 and the sealing element 27 is set in the groove. The plate 29 protrudes from the forward face of the 45 abutment 24 and the sealing element 27 is located immediately in front of the flap guiding surfaces 25. The sealing element 27 is in the form of an annular or continuous tube of rubber, or the like, adapted to yield and flex. The sealing element 27 arranged as just described, is engageable by the rear edge portion of the carton X to assure an effective seal with the carton. As illustrated in Fig. 1, the portion of the carton X occurring where its flaps F join its body, seal 50 with the sealing element 27 to effectively prevent the appreciable loss or escape of the refrigerant from the carton. The groove 30 is of substantially the same shape as the carton, that is, in the case illustrated the groove 30 is rectangular 55 or square and the sealing element 27 conforms to the shape of the groove to correctly seal with the rectangular carton X. The plate 29 extends forwardly beyond the sealing element 27 so that its forward face lies in the plane occupied by the forward edge of the carton X. With this arrangement the plate 29 substantially fully occupies or closes the forward end of the carton X. The means 11 may further include a plunger or follower 31 for assisting in the insertion of 60 the carton X and means for retaining the car-

ton in its refrigerant receiving position. The follower 31 is proportioned to slidably or shiftably operate in the opening 17 and has a flat rear face for pressing against the end of the carton X. The edge of the follower 31 is preferably thickened to have substantial cooperation with the wall of the opening 17. The means for retaining the carton X in place to receive the CO₂ is preferably such that cartons of different sizes, capacities or lengths may be correctly positioned for the reception of the CO₂. In the construction illustrated the retaining means comprises a pair of bolts 32 slidable through guides 33 on the forward side of the follower 31 and adapted to project through openings 34 in opposite edge portions of the follower. Flanges 35 are provided on the inner end portions of the bolts 32 and a spring 36 is arranged under compression between the spaced flanges 35 to urge the bolts 32 outwardly. The flanges 35 form handles by means of which the bolts 32 may be retracted. Longitudinally spaced sets or pairs of openings 37 are provided in the upper and lower walls 15 for the reception of the protruding portions of the bolts 32. The innermost pair of openings 37 is adapted to receive the bolts 32 to retain or position the follower 31 where it holds the smallest or the shortest carton X in place to receive the carbon dioxide. The outermost pair of openings 37 is adapted to receive the bolts 32 to hold the follower 31 in place where it retains the largest or the longest carton for the reception of the carbon dioxide. By grasping the flanges 35 the bolts 32 may be retracted to permit the insertion of the follower 31 in the opening 17 behind the carton X and the follower may be pushed inwardly to move the carton X to its final carbon dioxide receiving position whereupon the flanges 35 may be released so that the spring 36 moves the bolts into the correct openings 37. Longitudinal slots 38 may be provided in the side walls 15 to render the carton X accessible for easy removal following the withdrawal of the follower 31.

The means 12 is a duct system and valve means for conducting the CO₂ to the carton X in the compartment A and is under the control of the operating means 13. The means 12 includes a valve V in the compartment B. The body of the valve V may be secured to a suitable base 43 which in turn may be fixed to the partition 20. The valve V has an inlet fitting 49 at one end and a lateral outlet 50 between its ends. A needle 51 in the valve V is adapted to control or close the inlet. The stem 52 of the needle 51 extends through a gland 53 in an end of the valve body and carries spaced nuts 54. A lever 55 is pivoted on a suitable bracket 56 and has a yoke 57 co-operable with the needle stem 52 between the nuts 54. Spring means is provided for closing the needle 51 of the valve V. This spring means includes a cylinder 58 mounted on the base 43 and a plunger 59 projecting from an end of the cylinder. A spring 60 is arranged in the cylinder 58 under compression and acts on the plunger 59 to force the same outwardly. The outer end of the plunger 59 engages the lever 55 and, acting through the lever, serves to close the needle 51. The spring 60 also operates to return the operating means 13, as will be subsequently described.

The CO₂ may be held under pressure in a container or tank T and this tank may be located at a convenient point adjacent the device. A conduit 61 leads from the supply or tank T to a fitting 62 on a case wall 18. A coiled tube or coil

63 is provided in the compartment C and has one end connected with the fitting 62 to receive the liquid carbon dioxide under pressure. The coil 63 acts as an expansion element and trap for the carbon dioxide and is preferably of substantial length and capacity. The limited expansion of the carbon dioxide in the coil 63 produces a pre-cooling action and the carbon dioxide is cooled before it reaches the valve V. A pipe or tube 64 extends from the coil 63 to the inlet 49 of the valve V to deliver the carbon dioxide to the valve. The tube 64 passes through an opening in the partition 20 which is closed by a split plate 65. It is preferred to thoroughly insulate the coil compartment C.

The means 12 further includes a nozzle system for discharging the CO₂ into the carton X to produce CO₂ snow or solidified carbon dioxide in the carton X. As best illustrated in Fig. 4 of the drawings, the carton X houses or holds the container Y which may be considered as containing a perishable product. The container Y is cylindrical and fits the square or rectangular carton X in such a manner that longitudinal corner spaces are left open or unoccupied in the carton. The nozzle system serves to discharge the carbon dioxide into these corner spaces and all other unoccupied parts of the carton X.

Nozzles 65 project from the forward face of the plate 29 and are spaced and related to protrude into the unoccupied corner portions of the carton X. The nozzles 65 have small spaced perforations for directing the CO₂ under pressure forwardly and laterally in such a manner that it rapidly expands with a correspondingly rapid cooling which in turn produces crystallization or solidification of most of the carbon dioxide. This action is well known to those skilled in the art and results in the production of what is known as CO₂ snow or solidified carbon dioxide. The nozzles 65 are carried by pipes or tubes 66 which pass rearwardly through openings 67 in the plate 29 and connect with a manifold 68 which in turn joins with the outlet 50 of the valve V. The manifold 68 extends through a suitable opening in the case partition 17. The openings 67 are considerably larger than the tubes 66 and form passages through the plate 29 which allow for the free escape of the carbon dioxide that fails to solidify in the container X. An opening 69 is provided in the partition 7 and constitutes a passage connecting the compartment C with the opening 28 of the abutment 24. The gaseous CO₂ passes from the openings 67 through the opening 28 and the opening 69 to discharge into the compartment C where it assists in pre-cooling the CO₂ in the tube 63. It will be seen that upon opening of the valve V the CO₂ under pressure is discharged from the nozzles 65 to produce solidified carbon dioxide or CO₂ snow in the carton X.

The operating means 13 is manually actuatable and is operable to open the valve V and to operate or initiate operation of the timing means 14. The operating means 13 includes a suitable bracket 70 fixed to the base 43 or any other suitable support and a lever 71 mounted on the bracket 70 by a pivot pin 72. The lever 71 extends through an opening 73 in a side wall 18 of the case 10 and its projecting outer end portion is shaped to constitute a handle 74. The inner end of the lever 71 has a slit or slot 75. The operating means 13 further includes a link 76 pivotally secured to the base 43 by a pivot pin 77. A pin 78 is secured to the outer portion of the

link 76 and cooperates with the slot 75 so that operation of the lever 71 pivots the link. A pin 79 on the link 76 cooperates with a cam face 80 on the lever 55.

Forward manual pivoting of the outer arm of the lever 71 results in rearward pivoting of the link 76 and the cooperation of the pin 79 with the cam face 80 pivots the lever 57 to open the valve V. It is to be observed that the spring urged plunger 59 urges the rear arm of the lever 55 against the pin 79 and thus tends to pivot the link 76 in a direction to return the operating lever 71. The spring urged plunger 59 operates to return the manual operating lever 71 and to reclose the valve V when the lever is released by the operator. The handle portion 74 of the lever 71 may be readily grasped and moved forwardly to open the valve V and may be retained in the forward position to hold the valve V open as long as desired.

The timing means 14 is provided to indicate the time elapsing following opening of the valve V so that the operator may close the valve or may permit closing of the valve at any selected or given time and thus be assured that a given quantity of CO₂ snow is delivered to or formed in the carton X. In accordance with the invention the timing means 14 is actuated or put into operation by the means 13 and is related to the refrigerant discharge means 12 to indicate the time required to discharge sufficient CO₂ into the carton X to thoroughly preserve given quantities of products for given periods.

The means 14 includes a bracket 81 projecting laterally from the case 10 and carrying a housing 82. The housing 82 contains a clockworks 83 or its equivalent. The clockworks 83 includes a spring driven shaft 84 and a hand 85 fixed to the shaft. The clockworks 83 is adapted to drive or move the hand 85 rearwardly at a given rate and forward movement of the hand serves to tension the spring of the works 83 and thus store energy in the clockworks. A plate 86 is removably or replaceably held in channels 87 on the upper side of the housing 82 and has spaced markings or calibrations 88. The hand 85 cooperates with or moves past the calibrations 88. The plate 86 illustrated is designated "One pint" and is to be used where the machine is employed to refrigerate containers Y holding one pint. The plate 86 may be replaced by a similar plate calibrated to adapt the machine for the refrigeration of containers of other capacities, for example, one quart, three pint containers, etc. The calibrations 88 when read with the position of the hand 85 designate time intervals, that is, they designate the time intervals required to discharge given quantities of CO₂ into the container X to assure the refrigeration or preservation of the contents of the container Y for given periods. In the case illustrated one calibration 88 is designated "2 hrs." and the other calibration is designated "4 hrs." and when read with the hand 85 indicate that sufficient CO₂ snow has been supplied to the carton X to preserve the contents of the container Y for periods of two and four hours, respectively, when the valve V has been held open until the hand moves to the calibrations.

The means 14 further includes a drive means or actuating means for the clockworks 83. A link 90 is connected with the operating lever 71 by a pivot pin 91 and extends forwardly at one side of the housing 82. The link 90 has a hook-like projection 92 on its outer edge to cooperate

with a pin 93 on the hand 85 so that forward movement of the link moves the hand forwardly to store energy in the clockworks 83 and to bring the hand to its forward position. The link 90 has a pitched face 94 extending forwardly from the projection 92 and a curved face 95 extending rearwardly from the projection 92. The forward or outer end of the link 90 is sloping or pitched and normally cooperates with a stop pin 96 on the bracket 81. A leaf spring 97 is secured to the case 10 and cooperates with the inner edge of the link 90 to hold the link in its operative position. The outer end of the spring 97 may cooperate with a notch 98 in the inner edge of the link 90 to releasably hold the link and the operating lever 71 in their normal unactuated positions.

When the operating lever 71 is pulled forwardly by the operator the projection 92 of the link 90 cooperates with the pin 93 to move the hand 85 forwardly. During the first phase of this movement the engagement of the pitched forward end of the link 90 with the stop pin 96 swings or cams the link 90 toward the case 10 so that the curved edge 94 comes into engagement with the stop pin 96. The forward movement of the link 90 continues until the hand 85 has reached its forward position. The link 90 is directed or guided by the pin 96 so that the projection 92 leaves or moves out of cooperation with the pin 93 when the hand 85 reaches its forward position. At this time or immediately thereafter the projection 92 comes into engagement with the stop pin 96 to limit the forward movement of the link 90. When the pin 93 and the projection 92 are disengaged, as just described, the clockworks 83 immediately begins to move the hand 85 toward its normal position. The operator retains the lever 71 in its forward position until the hand 85 reaches a selected calibration 88 whereupon the lever 71 is released to permit closing of the valve V by the spring urged plunger 59. The arcuate or curved surface 95 of the link 90 allows the free return movement of the hand 85 when the link is in its forward position. A stop pin 99 limits the return movement of the clockworks hand 85.

In the operation of the device the container Y holding the product to be refrigerated, is arranged in the carton X and the carton is introduced into the opening 17 with its open end facing inwardly. The follower 31 is arranged behind the carton X and the flanges 35 are engaged to retract the bolts 32 and to push the follower 31 inwardly. As described above, the flaps F of the carton X open or spread somewhat through the resiliency of the carton material as they pass the surfaces 26 and the surfaces 25 serve to further open the flaps as the carton approaches its innermost position. The follower 31 is pushed inwardly until the inner end of the carton is in sealing engagement with the sealing element 27 whereupon the flanges 35 are released to allow the bolts 32 to enter the openings 37. The operator then moves the lever 71 forwardly to open the valve V. The lever is moved forwardly until the projection 92 comes into engagement with the stop pin 96, and is held in this position. As above described, the hand 85 is released to be returned under the action of the clockworks 83 just before the projection 92 engages the stop pin 96.

Upon opening the valve V the carbon dioxide flows through the coil 63, the tube 64, the valve 75, the manifold 68 and the tubes 66 to the nozzle

zles 65 where it is discharged to form solidified carbon dioxide or CO₂ snow. The nozzles 65 are located to discharge the CO₂ in the unoccupied corner portions of the carton X so that the refrigerant or snow is effectively distributed around the container Y. The discharge of the carbon dioxide from the nozzles 65 of course continues so long as the valve V remains open. If the product held by the container Y is to be preserved or refrigerated for two hours the operator holds the lever 71 in its forward position until the hand 85 reaches the calibration 88 designated "2 hrs." whereupon he releases the lever 71 to allow the valve V to close under the action of the spring urged plunger 59 as described above. On the other hand, if the contents of the container Y are to be refrigerated for four hours the lever 71 is maintained in its forward position until the hand 85 has reached the "4 hrs." calibration 88, whereupon the lever 71 is released to allow the valve V to be closed. It will be apparent that the lever 71 may be returned to its forward position following such closing of the valve V and retained in its forward position until the hand 85 reaches a selected calibration 88 so that sufficient refrigerant or CO₂ is discharged into the carton X to preserve the contents of the container Y for a longer period. Any of the CO₂ that does not solidify during the above operation flows out through the openings 67, 28 and 69 into the compartment C where it assists in pre-cooling the CO₂ passing through the coil 63. When the valve V has been closed the flanges 35 are engaged and moved toward one another by the operator, and the follower 34 is withdrawn from the opening 17. The carton X is then removed and its flaps F may be closed and sealed in the usual manner.

Having described only a typical preferred form and application of our invention, we do not wish to be limited or restricted to the specific details herein set forth, but wish to reserve to ourselves any variations or modifications that may appear to those skilled in the art or fall within the scope of the following claims:

Having described our invention, we claim:

1. A device for providing a refrigerant in a container having open end flaps comprising a case having a compartment for receiving the container, abutment means in the compartment engageable by the flaps at the inner end of the container to spread the same when the container is moved inwardly in the compartment, sealing means on the case for sealing with the inner end of the container, and means for introducing refrigerant into the open inner end of the container.

2. A device for providing a refrigerant in a container having an open end provided with closure flaps comprising a case having a compartment for receiving the container, abutment means in the compartment engageable by the flaps at said open end of the container to spread the same when the container is moved inwardly in the compartment, a sealing element for sealing with the container where said flaps join the container body and substantially corresponding in shape to the open end of the container, and means for introducing refrigerant into the open end of the container when the container and sealing element are in contact.

3. A device for providing a refrigerant in a container having an open inner end provided with flaps comprising a case having a compartment for receiving the container, abutment means in the compartment engageable by the flaps at the

inner end of the container to spread the same when the container is moved inwardly in the compartment, a sealing element supported in the case for sealing with the container where said flaps join the container body, means for retaining the container in the position where it is in contact with the sealing element, and means for introducing refrigerant into the inner end of the container when the container and sealing element are in contact.

4. A device for introducing a refrigerant into a container having open end flaps on at least one end comprising a case having a compartment whose outer portion is shaped to receive and guide the container and whose inner portion is enlarged, a flaring forwardly facing abutment in the inner portion of the compartment operable to spread said flaps when the container is moved inwardly in the compartment so that the flaps extend laterally in the enlarged portion of the compartment, and means for introducing refrigerant into the inner end of the container.

5. A device for introducing a refrigerant into a polygonal outer container housing a cylindrical inner container comprising a body having an opening for receiving the outer container, spaced nozzles at the inner end of the opening positioned to discharge into the corner portions of the outer container, and means conducting the refrigerant to the nozzles.

6. A device for introducing a refrigerant into an outer container housing an inner container, there being spaces in the corner portions of the outer container and at least one end of the outer container being open, the device comprising a body having an opening substantially corresponding in shape to the outer container to receive the outer container, and refrigerant discharging nozzles positioned at the inner wall of the opening to project into said corner spaces of the outer container through said open end of the outer container.

7. A device for introducing refrigerant into a container comprising a case having a compartment for receiving the container, a second compartment behind the first named compartment, and a third compartment behind the said first named compartment, a coil in the said third compartment for receiving the refrigerant from a source of the same, nozzles for discharging the refrigerant into the container in said first named compartment, a duct system for conducting the refrigerant from the coil to the nozzles, and a valve means in said second compartment controlling the duct system, the case having an opening allowing the escape of excess refrigerant from said first named compartment into said third compartment.

8. A device for introducing refrigerant into a container having an open end comprising a case having an opening conforming in shape to the container and adapted to closely receive the container, the outer end of the opening being open to receive the container, a nozzle in the case directed outwardly toward said outer end of the opening for discharging the refrigerant into the container when the same is positioned in the opening, a sealing element in the case at the inner end of the opening for sealing with the inner end face of the positioned container, and means for cooperating with the outer end of the container to retain the container in position in cooperation with the sealing element to receive the refrigerant.

9. A device for introducing refrigerant into a

container having an open end comprising a case having an opening for receiving the container, a nozzle in the case for discharging the refrigerant into the container when the same is positioned in the opening, a sealing element in the case for sealing with the inner end of the positioned container, and means for maintaining the container in position in cooperation with the sealing element to receive the refrigerant comprising a follower shiftable in the opening to bear against the outer end of the container, and latch means releasably holding the follower in a position where it maintains the container in the refrigerant.

10. A device for introducing refrigerant into a container having an open end comprising a case having an opening for receiving the container, a nozzle in the case for discharging the refrigerant into the container when the same is positioned in the opening, a sealing element in the case for sealing with the inner end of the positioned container, and means for maintaining the container in position in cooperation with the sealing element to receive the refrigerant comprising a follower shiftable in the opening to bear against the outer end of the container, and releasable means for holding the follower in any one of a plurality of longitudinally spaced positions where it maintains the container in the refrigerant receiving position.

11. A device for introducing a refrigerant into a container comprising a case for receiving the container, a nozzle carried by the case for discharging the refrigerant into the container, a normally closed valve governing the delivery of the refrigerant to the container, manually operable means for opening the valve and for manually holding the valve open, and a timing means put into operation by the manual actuation of the first named means and operable to indicate the time the valve is manually held open.

12. A device for introducing a refrigerant into a container comprising a case for receiving the container, a nozzle carried by the case for discharging the refrigerant into the container, a normally closed valve governing the delivery of the refrigerant to the container, manually operable means for opening the valve and for manually holding the valve open, timing means operable to indicate the elapse of given time intervals, and an operative connection between the first named means and the timing means whereby the

timing means is put into operation when the valve is opened.

13. A device for introducing a refrigerant into a container comprising a case for receiving the container, means for retaining the container in a given position in the case, a nozzle carried by the case for discharging the refrigerant into the container, a normally closed valve governing the delivery of the refrigerant to the container, manual means for opening the valve and adapted to be held by the operator to hold the valve open, means for automatically closing the valve upon the release of the manual means, timing means operable to indicate the elapse of given time intervals, and means actuated by operation of the manual means to initiate operation of the timing means.

14. A device for introducing a refrigerant into a container comprising a case for receiving the container, a nozzle carried by the case for discharging the refrigerant into the container, a normally closed valve governing the delivery of the refrigerant to the container, manual means for opening the valve and adapted to be held by the operator to hold the valve open, means for automatically closing the valve upon the release of the manual means, timing means operable to indicate the elapse of given time intervals comprising a clockworks, calibrations, and an indicating element moved by the clockworks and co-operating with the calibrations, and means operated by the manual means for storing energy in the clockworks to drive the same and for moving the indicating element to position for movement across the calibrations.

15. A device for providing a refrigerant in a container having an open end comprising a body having a compartment for receiving and confining the container, the outer end of the compartment being open to admit the container, sealing means in the body facing outwardly at the inner end of the compartment to be engageable by the end face of the container at the open end of the container to provide a seal between the container and body when the container is positioned in the body, and means for discharging a refrigerant into said open end of the container when the same is positioned in the compartment.
